UNITED STATES PATENT OFFICE.

THEOPHILUS TUCKER, OF OAKLAND, CALIFORNIA.

SUBMARINE PROJECTILE.

No. 882,980.

Specification of Letters Patent. Patented March 24, 1908.

Application filed December 18, 1907. Serial No. 407,003.

To all whom it may concern:

Be it known that I, THEOPHILUS TUCKER, a citizen of the United States, and a resident of Oakland, in the county of Alameda and State of California, (whose post-office address is No. 12 Mead avenue, Oakland, California,) have invented Improvements in Submarine Projectiles, of which the following is a specification.

10 This invention relates to a novel construction of shell or projectile having among other novel and useful features the peculiar function of penetrating the surface of a body of water when striking the same at an angle, 15 and of maintaining its course through the water at a greater or less depth below the surface. In addition to this feature which gives the invention a value for submarine purposes, this projectile has the function of 20 cutting its way through the water after submergence, and of regulating the extent of its submergence, without being diverted from a true course of trajectory.

The novel points and features of the invention consist in a shell or projectile having a substantially cylindrical hollow body, open from end to end, with slits or relatively narrow apertures in the walls of the shell at intervals around the circumference, and generally longitudinal of the body, and a plurality of spirally-set blades or prongs on the head.

The cylindrical body below is provided with spirally-set flukes or tail-pieces on the butt, or rear end, and the rear end of the shell 35 is temporarily closed by a separable break-piece which is adapted by its structure to become detached and separate itself from the butt or rear end after the projectile leaves the gun and before it strikes the water.

40 In addition to these novel features the invention embraces other novel points which will be more fully described hereinafter, and pointed out in the claims at the end of this specification.

45 The accompanying drawings illustrate my invention both as embodied in a shell to be fired from a gun of large caliber and constructed to explode on striking an object; and also as embodied in a shell provided with 50 a firing-device that is adapted to explode the shell by the chemical action of the water coming in contact with the firing-device.

Figure 1 represents the shell in side elevation with the breech-block in place on the rear end ready for firing the shell from a gun. 55 Fig. 2 is a side view of the breech-block detached from the shell, and showing its position with relation to the flukes or tail-pieces on the end of the shell. Fig. 3 is a perspective-view on an enlarged scale looking into 60 the front end of the shell, the breech-block being omitted from the rear end. Fig. 4 is a longitudinal section through the center of the shell with the breech-block removed from the rear end. Fig. 5 is a cross-section through 65 the line 5—5, Fig. 1. Fig. 6 is a cross-section through the line 6—6, Fig. 1. Fig. 7 is a cross-section through the line 7—7, Fig. 1. Fig. 8 is an end view of the plug looking at the front-end. Fig. 9 is a longitudinal-section 70 through the shell showing the chambers in the walls to contain charges of an explosive and the ducts or passages for fuses. Fig. 10 is a transverse section through the body on the line 10—10, Fig. 9. Fig. 11 is an end 75 view of the body of the shell, with the head removed, showing the screw-threaded socket to which the head is fitted.

The body *a* of this shell is cylindrical at any point of cross-section that may be taken in a 80 plane at right angles to the longitudinal axis of the body, as for example, on the line 5—5 Fig. 1, where the surface circumferentially is included or inscribed within a true circle, and extending axially through the body 85 from end to end is a passage *d* having the same diameter for a portion of its length from the front and back to a point about one-half of the length of the passage; but for the remaining portion the passage is gradually 90 contracted to a conical form for about the rear half of the distance from head to tail.

In the walls of the shell are formed, relatively long and narrow slots *c* opening through the body into the axial passage *d* at 95 uniform distances apart around the circumference. These openings are for the purpose of affording free passage and ample escape from the axial passage, for the air entering at the front of the shell during the first portion of its flight and before the breech-block on the tail of the shell is separated from it; and also for giving full outlet and discharge afterwards for the water that may be taken 100

in at the front end, when the shell passes into and travels through the water. In addition to these outlets from the hollow center through the body of the shell for easement 5 of the air and water that may enter the body, these slots are disposed on spiral lines around the longitudinal axis, with an inclination across the axis in the direction of the rotating motion which the shell receives from the 10 rifling of the gun in being fired.

The ribs *g* which alternate with the slots *c* are spirally disposed on the circumference of the shell and are joined together at the front end. At that end the head *b* of the shell is 15 united to the body *a*, by the annular portion *m* on the body in which a threaded socket *p* takes the threaded end of the head *b*.

The ribs *g* at the rear end merge into and are practically continuations of the flukes *f* 20 in a forward direction, and the last mentioned parts extending from the body are inclined to the axis of the body so as to have a spiral form, the same as the ribs *g*.

On the head or leading end of the body are 25 blades or prongs *n* corresponding in number to the spiral ribs on the body, and each blade or prong is formed with spiral faces and with tapering sides springing from the base where the blade or prong joins the body of the shell 30 outward to the point or leading end; such spiral face being gradually reduced in width, as illustrated in Figs. 1 and 4. These blades *n* are the same as the flukes *f*, and with the same inclination generally to the longitudinal 35 axis of the body.

The edges of each spiral rib at the leading end are higher than at the rear end, as seen in the cross-section, Figs. 5 and 6, thereby producing a fin or thin projecting edge *s* along 40 the circumference and giving the outer surface of each rib an inclination from the fin *s* to the rear edge *t*.

The blades *n* on the head, and the flukes *f* on the tail of the shell, have the same form 45 of surface as illustrated in Figs. 3 and 7. The leading edges *s*¹ of the blades *n* and the corresponding edges *s*² of the flukes are higher or are at a greater distance radially from the axis than are the rear edges *t*¹ and *t*².

50 As thus formed it will be seen that the shell is a skeleton structure, having annular front and rear ends united by spiral ribs which continue beyond the annular portions of the body in spirally-set blades on the head, and flukes on the tail or rear end.

The explosive function of this shell is characterized by chambers or passages formed within the walls or solid portions of the structure and communicating with apertures in the external surface at different points, where cavities or recesses are provided to contain a detonating cap or firing-device. In this feature of the invention provision is

made for exploding the shell by percussion at the moment of impact, by fixing a percussion cap 2 in a cavity in the point of one or more of the blades. And as an additional means to insure exploding the charge at the proper instant for obtaining the greatest effect of the projectile, the chambers containing the explosives are connected by a fuse with a cavity 8 in the outer surface of the body in which is placed a charge of potassium in the form of a capsule. This charge is adapted to be fired by contact with the water 75 in the well-known manner.

The chambers 3 in the body *a* of the shell extend from a common groove or cavity 4 in the socket, into the solid metal of the ribs; and in the head *b*, and its blades corresponding chambers 5 run longitudinally into the wells. These chambers 5 are consequently connected together by the groove 4, when the screw-threaded end of the head is screwed into the socket on the end of the 85 body; and by laying a fuse in the groove and connecting the same with the cavity 6 in the prong containing a detonating charge, all the charges are fired at the same instant.

If a time-explosion is desired, as by the 90 employment of a potassium capsule, which will fire the fuse by chemical action on contact with the water, the fuse in the groove is connected with a cavity 8 in the forward end of the slot *e* into which the capsule is fixed at 95 the time the shell is to be fired. These firing agents may be placed and connected with the charges in greater or less number, as found desirable to insure the best explosive effect of the projectile, whether at the moment of contact with the object, or at any required moment during its travel beneath the surface of the water before striking the object.

The explosive function of this shell as secured by the construction illustrated in Figs. 9, 10 and 11, and last above described, is in addition to its penetrating properties, and the quality of driving and maintaining its course below the surface which result from 110 the peculiar spiral form and the skeleton-like construction of the shell. And the invention embraces therefore a shell having the property of exploding and a projectile adapted to act by penetration only.

In order to obtain the required effect of the firing charge on the projectile, the rear end of the axial passage in the body is temporarily closed by the breech-piece or block, which combines in its construction several 120 novel features, principally in being formed or provided with projections 10 of proper shape and dimensions to fit in the spaces between the flukes *f* on the tail of the shell, and recesses 12 to receive the flukes. The parts 125 are properly shaped to fit over the flukes and

into the reëntering curves on the end of the shell, and at the same time the block is sufficiently loose to allow it to become detached and separate itself from the body of the shell 5 in the flight of the projectile.

The base of the block is solid, and the exterior surface is surrounded by a band 14 of soft metal to fill the rifling of the gun. On the rear end of the block is a sunken knob or 10 hand-grip 15 for lifting and setting the block in place on the end of the body, preparatory to inserting the projectile in the gun. The form of this block is shown in the side elevation Figs. 1 and 2 and in the enlarged front 15 view Fig. 8. In the latter view is illustrated the arrangement of the projections and recesses which are made to correspond with the spiral form and angular disposition of the ribs or solid portions of the body of the shell. 20 The leading edge of each prong or projection 10 that enters the space between the two flukes therefore stands above the surface of the fluke in front of it, as seen at 16, Fig. 1; and the leading edge s^1 of the fluke is 25 higher or is located at a greater distance from the axis than the back edge t^1 , so as to be practically flush with the rear edge of the projecting member 10 of the block against which it lies. The standing edge 16 thus 30 presents to a certain extent a greater resistance to the air than is presented by the body of the shell nearest the block, as the projectile leaves the gun. The effect of this is to facilitate the separation of the block from 35 the shell by the air-pressure within the axial passage, and also by the force of gravity, tending to cause the block to slip off and readily drop quickly away.

What I claim and desire to secure by Letters Patent, is,—

1. A projectile having a body composed of longitudinally disposed ribs separated by perforations, and an axial passage extending through the body from end to end.

2. A projectile having a body composed of longitudinally disposed ribs alternating with open spaces, an axial passage open from end to end of the body, and a head having prongs corresponding in number with the ribs.

3. A projectile having a body composed of longitudinally disposed ribs alternating with open spaces, an axial passage open from end to end of the body and a tail terminating in fluke-like projections.

4. A projectile having a body composed of spirally set ribs separated by perforations, and a passage extending axially through the body from end to end.

5. A projectile having a body composed of spirally set ribs separated by perforations, a passage extending axially from end to end of the body and a head having spirally-set prongs and an open center.

6. A projectile having a body composed of spirally-set ribs separated by perforations, a 65 passage extending axially from end to end of the body, and fluke-like projections on the rear end, in combination with a head having a hollow center and spirally set prongs corresponding in number with the ribs of the body.

7. A projectile having a passage extending axially through the body from end to end, longitudinally disposed slots in the walls opening into the axial passage, a head having projecting prongs alternating with reëntering spaces, and a tail having rearwardly 70 extending flukes.

8. A projectile having a passage extending axially through the body, longitudinally disposed slots in the walls opening into the axial passage, the solid portion of the body between the slots being inclined to the axis and having a standing edge on the circumference following the line of the slot.

9. A projectile having a passage extending axially through the body, spirally-set slots in the walls opening into the axial passage, the solid portions of the body between the slots being inclined uniformly to the axis and having greater elevation on the circumference along the leading edge than at the following edge of the solid portion.

10. A projectile having a passage extending axially through the body, and longitudinally disposed slots opening into the axial passage and inclined to the axis, the said body having a tapering shape internally from the head towards the tail, and the exterior surface of the portions between the 100 slots being inclined circumferentially.

11. A projectile having a passage extending axially through the body, apertures in the annular wall opening into the axial passage, a chamber in the solid portion of the 105 annular wall containing an explosive, and an exploding device on the leading end of the shell adapted to fire the explosive.

12. A projectile comprising a body having a passage extending through it from end to end and longitudinally disposed slots in the walls opening into the said passage, a head having a plurality of prongs projecting from the leading end, said prongs being spirally-set with relation to the axis of the projectile, 110 chambers in the annular walls of the body and the head containing charges of an explosive, a fuse-holding passage connecting said chambers, and a firing device in the end of one or more of the prongs connected with 115 said fuse and adapted to explode the charges 120 by percussion.

13. A projectile comprising a body having longitudinally disposed ribs, an axial passage extending through the body for the entire 125 length thereof, apertures in the walls of the

- body communicating with the axial passage, a separable head having a plurality of spirally-set prongs, a tail-piece provided with spirally-set flakes and a detachable tail-block.
- 6 14. A projectile having an axial passage open from end to end of the body, apertures in the circumferential walls of the body opening into the passage, flukes on the end of the body extending rearwardly and a separable
10 breech-block having a closed end and spaced

projections alternating with recesses which are adapted to interlock with the flukes.

In testimony that I claim the foregoing, I sign my name in the presence of two witnesses.
